UNITED STATES PATENT OFFICE.

PETER J. GARRETT, OF MORGANTOWN, WEST VIRGINIA.

ADJUSTABLE WINDOW-SHADE BRACKET.

Application filed June 4, 1923. Serial No. 643,214.

To all whom it may concern:

Be it known that I, PETER J. GARRETT, a citizen of the United States, residing at Morgantown, in the county of Monongalia and State of West Virginia, have invented 5 certain new and useful Improvements in Adjustable Window-Shade Brackets, of which the following is a specification.

This invention has reference to adjustable 10 window shade holders, and its object is to provide means whereby the window shade or shades may be supported in brackets made fast to the window casing in such manner that the shade holder may be sustained either singly or in pairs as the case 15 may be.

In accordance with the invention, there is 20 provided a basic member with a plate sustained thereby so that either one or more rollers may be supported to sustain one or more shades, either singly or in tandem.

The invention will be best understood 25 from a consideration of the following detailed description taken in connection with the accompanying drawing, forming part of this specification, with the understanding that the invention is not confined to any strict conformity with the showing of the drawings, but may be changed and modified 30 so long as such changes and modifications mark no material departure from the salient features of the invention as expressed in the appended claim.

In the drawing:

35 Figure 1—is a plan view of an adjustable window shade bracket embodying the invention.

Figure 2—is a side elevation thereof.

40 Figure 3—is a plan view of the window shade bracket, as viewed from the opposite side to that shown in Figure 1.

Figure 4—is a section on the line 4—4 of Fig. 1.

45 Figure 5—is a plan view of a double shade bracket.

Referring to the drawing, there is shown a plate 1, which may be a metal plate of elongated shape, provided at opposite ends with counter-bored screw holes 2, by means

of which the plate may be made fast to a 50 window casing or other support.

Extending lengthwise through the plate 1 is a screw arbor 3 journaled near the ends in upright posts 4 being freely rotatable in said posts.

55 The arbor 3 is provided near one end with a milled wheel 5, by means of which rotating movement is imparted to the arbor, and such arbor has screw threaded engagement in a block 6 through the greater portion of the length of the arbor. The block 6 is formed with a basic portion 7 engaging the plate 1. The basic portion 7 of the block 6 carries another plate 8 in right angular relation to the block 6, so that the 60 block 6 and the plate 8 are held against turning, and the plate 8 projects through a longitudinal slot 9 in the plate 1, so that the block 6 and plate 8 are caused to move lengthwise of the slot 9, because of the basic 65 portion 7 of the block 6 and the narrow width of the slot 9, the plate 8 is prevented from turning while being propelled along the plate 1. The plate 1 is provided adjacent one end with an opening 13 through 70 which a portion of the milled wheel 5 projects in order that this milled wheel may be operated from either side of the plate.

75 In the modification shown in Figure 5, there are two screw threaded arbors 3^a and 3^b in tandem and both arbors are individually rotatable about the longitudinal axis by means of milled wheels 10, while in the form shown in Figures 1 to 3, but a single arbor 3 is employed.

80 In Figure 1 and associated figures, there is shown a plate having a single perforation 11 designed to receive the pin usually employed in the curtain fixtures of a shade, and in Figure 5, there are shown other 85 shade fixtures 12 to hold the customary angle slot employed in shade fixtures, to prevent rotation of the corresponding end of the shade roller.

90 Having thus described my invention, what I claim as new, and desire to secure by Letters-Patent, is:

A curtain fixture including an elongated

plate having a slot disposed longitudinally thereof, posts mounted at one side of the plate and disposed beyond the ends of the slots, the plate being provided with an opening disposed in alignment with the slot, a threaded arbor journaled in the posts, a knurled wheel mounted upon the arbor and having a portion of its periphery pass-

ing through the opening in the plate, a block 10 slidably mounted in the slot and having a threaded opening which snugly receives the thread of the arbor, and a plate carried by the block for supporting a shade roller.

In testimony whereof I affix my signature.

PETER J. GARRETT.
